ABSTRACT

A pilfer-proof closure for use in combination with a container having a threaded neck portion and an annular flange below the threaded portion, comprising a body having an internally threaded upper portion and a lower skirt portion. A flexible locking member attached to the inside of the body by frangible connecting means and protected by the skirt is adapted to slide over the container flange as the cap is threaded on whereby the locking member snaps into place underneath the flange to lock the closure onto the container. When the closure is unthreaded from the container, the frangible connecting means are broken to completely disconnect the locking member from the inside of the closure. A viewing opening in the lower portion of the body permits visual observation of the locking member when the closure is threaded on the container to determine whether or not the container has been tampered with.

PILFER-PROOF CLOSURE FOR CONTAINERS**BACKGROUND OF THE INVENTION****1. Field of Invention**

This invention relates generally to closures for containers and, more particularly, to a pilfer-proof closure having an internal locking member protected by the outer walls of the body of the closure when it is threaded onto a container and provided with a viewing window to determine whether authorized tampering with the container has occurred.

2. Description of the Prior Art

Prior art pilfer-indicating closures for containers heretofore known have been beset with disadvantages. For example, such prior art closures provided with outer frangible locking members have not provided sufficient protection for the locking members to prevent unauthorized tampering with the closure without breaking the locking member. Other such prior art closures having internal locking members protected by an outer wall have not provided any means for viewing the locking member while the closure is in place to determine whether the closure has been tampered with. Still other such prior art closures must be completely fractured or broken to gain access to the container and thus are not capable of being reused after the initial opening of the container. Moreover, other such prior art closures have been relatively complicated in construction. The present invention represents an improvement over such prior art closures.

SUMMARY OF THE INVENTION

Among the objects of the present invention is to avoid the disadvantages of prior art pilfer-proof container closures and to provide an improved pilfer-proof closure having an internal locking member protected by the outer walls of the closure, while still permitting visual observation of the locking member through a viewing window to determine whether the closure has been tampered with.

A further object of the invention is to provide a pilfer-proof container closure which may be reused after the container has been initially opened. Another important object of the invention is to provide a pilfer-proof closure which is simple in construction and economical to fabricate.

According to the present invention there is provided a pilfer-proof closure for use in combination with a container having a threaded neck portion and an annular flange below the threaded portion. The closure is comprised of a body having an internally threaded upper portion and a lower skirt portion. A flexible locking member attached to the inside of the closure body by frangible connecting means and protected by the skirt is adapted to flex or expand and subsequently slide over the container flange as the closure is threaded onto the container. A circular gap between the locking member and the skirt provides room for the locking member to flex. As the locking member slides over the flange, it snaps into place in a groove underneath the flange to lock the closure in place on the container. When the closure is removed, interference between the container flange and the locking member causes the frangible connecting means to break so that the locking member becomes completely disconnected from the body and falls down around the neck of the container as the closure is unthreaded therefrom.

A viewing window is provided in the skirt portion of the body of the closure to permit visual observation of the locking member when the closure is in locked position to determine whether the container has been tampered with or unauthorizedly opened after the closure has been initially threaded onto the container. The walls of the body protect the internal locking member to prevent the locking member from being manipulated to unthread the closure without breaking the locking member. The container may be provided with either an annular rib or a wide shoulder below the annular flange which engages the bottom of the closure body when the closure is in locked position to prevent unauthorized tampering with the locking member.

BRIEF DESCRIPTION OF THE DRAWINGS

Other objects and advantages will become apparent by reference to the detailed description of the invention and the accompanying drawings which follow, 20 wherein:

FIG. 1 is a front elevational view of a container closure constructed according to the principles of the present invention, showing the closure in locked position on a container;

FIG. 2 is a cross-sectional view taken along line 2-2 of FIG. 1, showing the closure in locked position on the container;

FIG. 3 is a cross-sectional view taken along line 3-3 of FIG. 2;

FIG. 4 is a cross-sectional view taken along line 4-4 of FIG. 2;

FIG. 5 is a front elevational view of the upper portion of the container, showing the closure in cross-section prior to being threaded on the container;

FIG. 6 is a front elevational view showing the closure partially threaded onto the container with the locking member sliding over the container flange;

FIG. 7 is a front elevational view showing the closure partially unthreaded with the locking member disconnected from the inside of the closure body;

FIG. 8 is a cross-sectional, front elevational view of a further embodiment of the closure;

FIG. 9 is a cross-sectional front elevational view of a still further embodiment of the closure; and,

FIG. 10 is a front elevational view of the closure of the present invention in use on a container having a wide shoulder.

DESCRIPTION OF THE PREFERRED EMBODIMENTS

Referring to the drawings there is shown a pilfer-proof container closure 10 for use in combination with a suitable container shown in the form of a bottle 11. The container may be constructed of any suitable material such as glass or plastic. In the form of the invention shown in FIGS. 1 through 7, the container 11 is comprised of a lower body portion 12 and an upper neck portion 13. Referring to FIGS. 2 and 5, the container neck portion 13 includes an upper threaded portion 14 followed by an annular flange 15 just below the threaded portion 14. Annular flange 15 has a top surface 16 which slants downwardly and outwardly and a horizontal bottom surface 17 which extends from the neck 13 of the container out to the extremity of the flange where it meets the outer end of top surface 16.

An annular rib 18 is mounted on the neck 13 spaced axially below flange 17 to form a groove 19 between

the flange and the rib for a purpose to be discussed more fully hereinafter. Rib 18 has a diameter at least as great as the diameter of the bottom of closure 10.

Referring to FIGS. 2 through 5, the closure 10 is comprised of a body 21 having an internally threaded upper portion 22 and an integrally connected lower skirt portion 23. The skirt 23 has an upper portion 24 and a lower portion 25. Upper skirt portion 24 slants downwardly and outwardly from the internally threaded portion 22. Upper and lower skirt portions 24 and 25 are connected by horizontal rib 26.

A locking member 31 is attached inside of the closure body 21 to the inner bottom surface of horizontal rib 26, whereby the locking member is protected by lower portion 25 of the skirt 23. In the form of the invention shown in FIGS. 3 through 5, locking member 31 is comprised of two semi-circular segments 32 and 33 attached to horizontal rib 26 by a plurality of spaced frangible connecting webs 34. As indicated in FIGS. 5 and 6, the webs 34 may extend vertically downwardly from the inside of the horizontal rib 26, or as illustrated in FIG. 8, the webs 34 may extend horizontally inwardly from the inside of the rib 26. The segments 32 and 33 and the webs 34 are flexible to permit the locking member 31 to slide over container flange 15 when the closure is threaded onto the container. The segments 32 and 33, constituting locking member 31, are each constructed to have a flat horizontal top surface 35 and an inner bottom surface 36 which slants generally downwardly and outwardly from top surface 35. Closure 10, including locking member 31, may be fabricated as an integral unit by molding from a resilient plastic material such as polyethylene or polypropylene.

It is to be noted that a circular gap or space 27 is provided between the locking member 31 and the lower portion 25 of the skirt 23. This gap provides room for the locking member to flex outwardly a short distance over the container flange 15 when the closure is threaded onto the container. Conversely, the gap is small enough that the skirt 23 limits the extent to which the locking member can flex when the closure is unthreaded to prevent the locking member from flexing too far and simply sliding back over the container flange.

While locking member 31 has been described as comprised of two segments, it will be obvious that the locking member, if desired, may be constructed of a single element in the form of a ring 31 extending around the inside of the skirt 23 as shown in FIGS. 8 and 9. Moreover, the locking member 31 may be attached to rib 26 by a very thin, easily breakable plastic film or membrane 38 as shown in FIG. 9. If desired a plastic film may be used which is perforated as shown by the dashes 39 in FIG. 9.

One or more relatively narrow viewing windows 37 are provided in the skirt 23 of the closure body 21 to permit visual observation of the locking member 31 when the closure is threaded onto the container. In the preferred form of the invention, the viewing window 37 extends from the bottom or middle of the lower portion 25 of skirt 23 upwardly to a point intermediate of the top and the bottom of the lower skirt portion 25. While only a single viewing window is shown in the drawings, it is to be noted that an additional viewing window may be provided in the closure 20 if desired. An excess of viewing windows is undesirable in that it would permit tampering with the locking member. The operation of

threading and unthreading the pilfer-proof closure of the present invention is best described with reference to FIGS. 5 to 7.

As the closure 10 is initially threaded onto the container 11, the locking member 31 contacts container flange 15 and flexes or expands into gap 27 as it slides over the top surface 16 of the flange 15 as shown in FIG. 6. When the closure 10 is completely threaded onto the container neck 13, the locking member 31 snaps back into groove 19 under the flange 15 as shown in FIG. 2 to lock the closure in closed position on the container. When the closure is in closed position, the top surface 35 of the locking member is spaced a small distance from the bottom surface 17 of the flange. This permits easier removal of the closure in that less initial torque is required to initiate unthreading.

It is to be noted that the lower portion 25 of skirt 23 is of sufficient length to extend down and contact the container rib 18 when the closure is in locked position as shown in FIG. 2. The present invention affords a significant advantage in that adequate protection is provided for the locking member 31 to prevent any instrument from being inserted between the bottom of the skirt 23 and the rib 18, thus frustrating any attempt to manipulate the locking member to open the container without causing the locking member to break.

As shown in FIG. 7, when the closure is unthreaded from the container, the interference between the top surface 35 of the locking member 31 and the bottom surface 17 of container flange 15 causes the frangible connecting means to rupture or break, whereupon the locking member falls down around the neck of the container. After the closure has been completely removed from the container, the locking member may then be disposed of and the closure is still suitable for subsequent reuse for closing the container.

A further embodiment of the present invention is shown in FIG. 10 wherein the closure 10, having the same construction as that previously described is used in combination with a container 11, having an annular shoulder 41 spaced axially below the container flange 15. The shoulder 41 of the container has a diameter at least as great as the diameter of the skirt 23 of the closure, so that the bottom of the skirt 23 engages the top surface of the shoulder 41 when the closure is in its locked position on the container.

It is to be understood that the invention is not limited to the particular embodiments described and shown herein and that it includes any modification or equivalents within the scope of the appended claims.

We claim:

1. A pilfer-proof closure for use in combination with a container having a threaded neck portion and an annular flange below said threaded portion comprising:
  - a body having an internally threaded upper portion and a lower skirt portion,
  - a flexible locking member inside of said body protected by said skirt portion and spaced therefrom adapted to slide over said container flange as the closure is threaded onto said container,
  - said locking member having a top surface adapted to engage the bottom surface of said flange to lock the closure in place when the closure is completely threaded onto said container,
  - frangible connecting means for securing said locking member to the inside of said body so that said locking member will become completely disconnected

from said body when the closure is unthreaded from said container, and a viewing opening in said body to permit visual observation of said locking member to determine whether the container has been opened after the closure has initially been threaded thereon.

2. A pilfer-proof closure as defined in claim 1 wherein said locking member has a bottom surface slanting downwardly and outwardly from the top surface thereof to facilitate the sliding movement of said locking member over said container flange when the closure is threaded onto said container.

3. A pilfer-proof closure as defined in claim 1 wherein said locking member is comprised of a plurality of annular segments connected to the inside of said body.

4. A pilfer-proof closure as defined in claim 1 wherein said locking member is comprised of a continuous annular ring connected to the inside of said body.

5. A pilfer-proof closure as defined in claim 1 wherein said connecting means comprises a plurality of frangible webs connected at one end to the inside of said body and at the other end to said locking member.

6. A pilfer-proof closure as defined in claim 5 wherein said skirt portion includes a horizontal rib and said webs extend vertically downwardly therefrom.

7. A pilfer-proof closure as defined in claim 5 wherein said skirt portion includes a horizontal rib and said webs extend horizontally inwardly therefrom.

8. A pilfer-proof closure as defined in claim 1 wherein said connecting means comprises a thin plastic membrane.

9. A pilfer-proof closure as defined in claim 1 wherein said connecting means comprises a perforated plastic film.

10. A pilfer-proof closure as defined in claim 1 for use in combination with a container having an annular rib spaced from and below said container flange, said rib having a diameter at least as great as the diameter of said skirt portion, wherein said skirt portion is of sufficient length to engage the upper surface of said rib when the closure is threaded onto said container to locked position.

11. A pilfer-proof closure as defined in claim 1 for use in combination with a container having a body provided with a shoulder portion spaced from and below said annular flange and having a diameter at least as great as said skirt portion wherein said skirt portion is of sufficient length to engage said shoulder portion when the closure is threaded onto said container to locked position.
